DESIGN FOR A SET OF PLAYING CARDS

Dan Fillson and David Bud Crollard,
Fairbanks, Territory of Alaska

Application December 20, 1945, Serial No. 124,889

Term of patent 14 years

(Cl. D34—13)

To all whom it may concern:

Be it known that we, Dan Fillson and David Bud Crollard, citizens of the United States, residing at Fairbanks, Alaska, have invented a new, original, and ornamental Design for a Set of Playing Cards, of which the following is a specification, reference being had to the accompanying drawing, forming part thereof, in which Figure 1 is a face view of one suit of cards, Figure 2 of a second suit of cards, Figure 3 of a third suit of cards, and Figure 4 of a fourth suit of cards, showing our new design.

The cards are of no appreciable thickness and the backs of the cards are conventional.

We claim:

The ornamental design for a set of playing cards as shown and described.

We hereby appoint Herbert E. Smith, #1208 Old National Bank Building, Spokane, Washington, register No. 10,316, our attorney with full power of substitution and revocation to prosecute this application, to make alterations and amendments therein, to sign his name to the drawing, to receive the Letters Patent for the design, and to transact all business in the United States Patent Office connected therewith.

DAN FILLSON.
DAVID BUD CROLLARD.
